TAPE DISPENSER

Irvin J. Gershen, Springfield, N. J., assignor to Permacel
Tape Corporation, a corporation of New Jersey

Application November 4, 1955, Serial No. 38,729

Term of patent 14 years

(Cl. D74—1)

Fig. 1 is a side perspective view of a tape dispenser showing my new design;

Fig. 2 is a side elevational view thereof;

Fig. 3 is a top plan view;

Fig. 4 is a front elevational view; and

Fig. 5 is a rear elevational view thereof.

I claim:

The ornamental design for a tape dispenser, substantially as shown.
